US0D1054644S

(12) **United States Design Patent** (10) **Patent No.:** **US D1,054,644 S**
(45) **Date of Patent:** **** Dec. 17, 2024**

(54) **BASE FOR FABRIC SECURING SYSTEM**

(71) Applicant: **Brayniacs LLC**, Denver, CO (US)

(72) Inventor: **Cynthia Moltz Bray**, Denver, CO (US)

(73) Assignee: **Brayniacs LLC**, Denver, CO (US)

(**) Term: **15 Years**

(21) Appl. No.: **29/929,408**

(22) Filed: **Feb. 21, 2024**

Related U.S. Application Data

(63) Continuation of application No. 18/236,176, filed on Aug. 21, 2023, now Pat. No. 11,982,043, which is a continuation of application No. 18/074,910, filed on Dec. 5, 2022, now Pat. No. 11,732,400, which is a continuation of application No. 18/071,213, filed on Nov. 29, 2022, now Pat. No. 11,649,584, which is a continuation of application No. 17/367,904, filed on Jul. 6, 2021, now Pat. No. 11,608,585, which is a continuation of application No. 16/850,546, filed on Apr. 16, 2020, now Pat. No. 11,078,621.

CLAIM

The ornamental design for a base for fabric securing system, as shown and described.

DESCRIPTION

FIG. 1 is a perspective view of a base for fabric securing system showing my new design;

FIG. 2 is a front elevation view thereof;

FIG. 3 is a rear elevation view thereof;

FIG. 4 is a right side elevation view thereof;

FIG. 5 is a left side elevational view thereof;

FIG. 6 is a top plan view thereof; and,

FIG. 7 is a bottom plan view thereof.

The broken lines showing portions of the base for fabric securing system form no part of the claimed design.

1 Claim, 7 Drawing Sheets
